UNITED STATES PATENT OFFICE.

EDUARD LEISSNER, OF NEW YORK, N. Y., ASSIGNOR TO LEISSNER & LOUIS,
OF SAME PLACE.

DESIGN FOR WALL-PAPER.

SPECIFICATION forming part of Design No. 11,990, dated October 26, 1880.

Application filed July 31, 1880. Term of patent 3½ years.

To all whom it may concern:

Be it known that I, EDUARD LEISSNER, of the city of New York, in the county and State of New York, have invented a new and original Design for Wall-Paper, of which the following is a specification.

This invention relates to a new and original design for wall-paper and similar fabrics.

It consists in the novel grouping and configuration of the figures hereinafter more fully described.

The accompanying photograph illustrates a face view of wall-paper having my new design.

The separate figures A B C D, &c., are each made up of a series of concentric circles, the outside circle being of any desired diameter and determining the size of the particular figure, and the body of the figure being composed of circles one within another, a star being placed within the smallest circle, and dots between the points of the star within that circle. These circular figures are so arranged that the larger ones, as A A A, are placed alongside one another to form the background. Upon these are placed a smaller size of the circular figures, as B B B, &c., each one laid so as to lap over upon two or more of the figures A A A.

Upon the figures B B are laid other smaller

and similar figures, C C C, lapping over upon two or more of the figures A A A, &c., or B B 30 B, or A B, &c.

Similar and smaller figures D D D are placed on those already in position, and so on, and the different sizes of the circular figures are laid upon or lapped over on each other in any 35 desired manner, which will result in covering the whole surface of the paper with the figures, as shown in the photograph annexed, thereby producing a very unique and beautiful effect.

I claim—

1. The design for wall-paper, consisting of a circular figure, B, formed of a series of concentric circles with a star in its center, substantially as shown.
2. The design for wall-paper, consisting of 45 the figures A B C D, &c., laid upon and lapsing over one another, substantially as shown.
3. The design for a wall-paper, consisting of a circular figure, D, of concentric rings with a star in the center and dots between the points 50 of the star, substantially as shown.

EDUARD LEISSNER.
